Primary Examiner — Cathy A MacCormac(74) *Attorney, Agent, or Firm* — Montogomery Patent & Design, LLC; Robert C. Montgomery; Joseph T. Yaksich(57) **CLAIM**

The ornamental design for a remote control pet toy, as shown and described.

DESCRIPTION

FIG. 1 is a perspective view of a remote control pet toy, showing my new design;

FIG. 2 is a front view thereof with the rear view being identical;

FIG. 3 is a left side view thereof with the right side view being identical;

FIG. 4 is a top view thereof;

FIG. 5 is a bottom view thereof; and,

FIG. 6 is a bottom perspective view thereof.

The broken line showing of wheels is for the purpose of illustrating a remote control drive vehicle and forms no part of the claimed design.
